POSITIVE RELAY

Frederick D. Joesting, Oak Park, Ill., assignor to
Minneapolis-Honeywell Regulator Company,
Minneapolis, Minn., a corporation of Delaware

Application July 2, 1943, Serial No. 493,243

9 Claims. (Cl. 74—97)

This invention relates in general to a pneumatically operated relay and in particular to one of the "positive" type which effects a positive positioning of a valve mechanism in one of two positions or the other in response to increase or decrease of pressure to the relay to a predetermined point, the valve mechanism being thereby operable at only said predetermined point, regardless of the rate of supply or discharge of compressed air to the relay.

One object is to provide a comparatively simple snap acting mechanism for transferring the motion of a lever moving in response to pressure changes to an actuated element which controls the valve mechanism.

A further object is to provide a positive relay wherein a valve or the like controlled by the relay is operated to wide open or fully closed position in response to the relay, the relay being so designed that a three-way valve mechanism thereof may be connected for direct or reverse action of a valve controlled thereby or as a diverting relay operating a pair of valves selectively.

Another object is to provide pressure responsive means for actuating the relay, which means includes an adjustable range spring, the pressure responsive means being connected with an actuating lever in a novel manner and the pressure responsive means and range spring being mounted in alignment, so as to minimize the forces imposed on the actuating lever, whereby the lever may be of comparatively light construction. A relatively light toggle spring can be used to effect snap action between the lever and the valve mechanism, the construction lending itself particularly to ease of manufacture and assembly, and to the possibility of the control point being adjusted over substantially the entire range of pressures used in pneumatic control installations of this general type.

Still a further object is to provide a well balanced arrangement of parts in the snap acting mechanism whereby the actuating lever is pivoted to the frame of the control structure at two widely separated points and the operative connection between the pressure responsive means and the lever also includes a pair of pivots spaced a substantial distance from each other, the toggle spring connection between the lever and the valve mechanism being also arranged for good balance and an absence of lateral pressure on the pivots that would result in sluggishness of operation or loss of sensitivity.

A further object is to provide certain pivot connections which are installed in a novel manner so that a sleeve actuated by the pressure responsive means may fit in an opening of the actuating lever with the pivots initially received far enough in the sleeve to permit them to pass into the opening and thereafter spread apart to substantially fill the opening.

With these and other objects in view, my invention consists in the construction, arrangement and combination of the various parts of my device, whereby the objects contemplated are attained, as hereinafter more fully set forth, pointed out in my claims, and illustrated in the accompanying drawings, in which:

Figure 1 is an enlarged top plan view of a positive relay embodying my invention;

10 Figure 2 is a vertical, sectional view thereof as taken on the line 2—2 of Figure 1, and showing the parts in low pressure position;

Figure 3 is a similar, sectional view showing the parts in high pressure position;

15 Figure 4 is a horizontal, sectional view on the line 4—4 of Figure 3, showing the porting arrangement of the valves of the relay;

Figure 5 is a vertical, sectional view on the line 5—5 of Figure 3;

20 Figures 6, 7 and 8 are diagrammatic views showing my relay connected in a pneumatic system for use, respectively, as a direct relay, a reverse relay, and a diverting relay;

Figure 9 is a sectional view on the line 9—9 of Figure 3, showing a pair of pivots during one step of their installation, and

25 Figure 10 is a similar view showing the pivots in their final installed position.

On the accompanying drawings, I have used 30 the reference numeral 10 to indicate a base on which the mechanism of my positive relay is mounted. On the base 10, I mount a valve body 12, by means of screws 14 extending through bifurcated feet 16 of the valve body and threaded 35 into the base. The valve body 12 in turn serves as a mount for a pair of end castings 18 and 20 secured thereto as by screws 22 and 24, respectively.

The valve body 12 and the two castings 18 and 40 20, together with three cover plates 26, 28 and 30 secured in position by screws 32 having knurled heads, constitute a housing for the relay mechanism.

The casting 20 has therein a diaphragm chamber 34 spanned by a pressure responsive diaphragm 36. The diaphragm 36 is retained in position by a diaphragm casing 38 secured as by screws 40 to the casting 20. The edge of the diaphragm constitutes a gasket between the end casting 20 and the diaphragm casing 38. Within the casing 38, a diaphragm chamber 1^a is provided and it is in communication with a boss 1, which in turn constitutes an inlet for the diaphragm chamber 1^a as from a pipeline 42.

45 55 Against opposite sides of the center of the diaphragm, I provide discs 44 and 46 secured together as by riveting a stud 48 which extends from the disc 44 and through the diaphragm and the disc 46. The disc 44 also has a socket member 50 receiving one end of a stud 52. The other 60 end of the stud 52 is threaded into one end of a

sleeve 54. Against a flange 56 adjacent the opposite end of the sleeve 54, I seat an adjusting spring 58. The adjusting spring is interposed between the flange 56 and a second flange 69 formed on a sleeve 62. The sleeve 62 is threaded on an adjusting screw 64, the screw having a bearing portion 66 rotatable in an opening 68 of the end casting 18. The spring 58 urges the adjusting screw 64 to move toward the left and it is limited in such movement by a flange 70 formed on the screw and engaging a shoulder 72 of the casting 18.

From the construction of the parts just described, it will be obvious that the spring 58 (which is always under compression) keeps the flange 70 against the shoulder 72 and the right-hand end of the stud 52 in the socket 50 in opposition to any air pressure introduced from the pipe 42 into the diaphragm chamber 1^a. Overtravel of the diaphragm may be limited by an adjusting sleeve 74 screw-threaded into the casting 20 and surrounding the socket member 50, as shown in Figure 3. In the opposite direction, as shown in Figure 2, the disc 46 may seat against a boss 76 in the diaphragm casing 38, when the air pressure is relieved. The boss 76 is provided with radial grooves or is otherwise interrupted to prevent seal-off of the air pressure from the line 42 to the chamber 1^a.

For purposes of determining the adjustment of the spring 58, I provide an upwardly extending pointer 78 on the sleeve 62 passing through a slot 80 in the cover plate 28. Suitable indicia may be provided on the cover plate, adjacent the slot, if desired, for determining the adjustment at any time. A change in adjustment is secured, of course, by rotating the adjustment screw 64 as by a screwdriver inserted into a slot 82 at the left-hand end of the screw.

The valve body 12 is provided with three openings 2, 3 and 4 (see Figure 4), into which air pipes or copper tube fittings may be screwed. Adjacent the openings 2 and 4 are valves, indicated generally at V² and V⁴. These valves, as shown in Figure 3, comprise stems which are slidably mounted in plugs 84 and 86 and heads which may seat against valve seats 88 and 90. The opening 3 in the valve body is common to both valves V² and V⁴ by means of a passageway 3^a from the opening 3 into a chamber 3^b. The chamber 3^b communicates with both of the valve seats 88 and 90.

The chamber 3^b has all but its top formed in the valve body 12, and a seal-off diaphragm 92 serves as the top of the chamber. The seal-off diaphragm 92 is confined between the valve body 12 and a cover plate 94, screws 95 passing upwardly through the valve body and being threaded into the cover plate for this purpose. The seal-off diaphragm 92 thereby forms a gasket around the chamber 3^b to prevent leakage.

The valves V² and V⁴ open into chambers 2^b and 4^b which communicate, respectively, through passageways 2^a and 4^a with the openings 2 and 4.

On the cover plate 94, I pivot an actuated lever 96 in the form of a relatively thick plate having a pair of downwardly extending ears 98 (see Figure 5). These ears are pivoted to the cover plate 94 by means of pivot screws 100, tightly threaded into the ears and having pinlike extensions 102 into an opening 104 drilled through the cover plate.

The actuated lever 96 carries a pair of screws 106 and 108 for opening the respective valves V² and V⁴. As shown in Figure 2, the screw 108 is

depressed for opening the valve V⁴ (the valve being spring loaded for normal closing) by contact of the lower end of the screw with a portion of the seal-off diaphragm 92 in an opening 112 of the cover plate 94. This portion of the diaphragm is accordingly depressed and engages the upper end of the valve V⁴ to lower it away from the seat 90 against the action of the valve spring.

10 Likewise in Figure 3, another portion of the diaphragm 92 in an opening 114 of the cover plate 94 is engaged by the screw 106 for opening the valve V², the screw 108 at the same time permitting the valve V⁴ to close under the action of its spring. In accordance with the description just completed, it is obvious that the opening 3 in the valve body 12 is in communication with the opening 2 when the opening 4 is closed off from the opening 3, the actuated lever 96 being in the position of Figure 3. Communication occurs between the openings 3 and 4 and the opening 3 is closed relative to the opening 2 when the actuated lever is in the position of Figure 2.

For automatically tilting the lever 96 in response to pressure on the diaphragm 36, I provide a toggle mechanism including an actuating lever 116 and a toggle spring 118. The actuating lever 116 is in the form of a plate having an opening 120 through which the sleeve 54 loosely extends and is bifurcated at its lower end to provide a pair of arms 122. The actuating lever 116 is pivoted on stationary pivots 124 formed on pivot screws 126. The screws 126 are tightly screwed into a pair of wings 128 formed on the end casting 20, the pivots of the screws extending into openings 130 of the lever 116.

The operative connection between the sleeve 54 and the lever 116 comprises a pair of pivot pins 132 formed on knurled studs 134, the studs being received in openings 136 of the sleeve 54 and the pivot pins 132 being received in openings 138 of the lever 116.

The mounting of the pivot pins 132 involve a problem due to the sleeve 54 being within the opening 120, and the lever 116 being made in one piece, instead of two pieces, which might be fastened together to surround the sleeve. In Figure 9, I illustrate how the studs 134 are pushed too far into the openings 136 of the sleeve 54, and a flat, bladelike tool 140 thrust into the opening of the sleeve 54 and then rotated to the position of Figure 10 after the pivot pins 132 are aligned with the openings 138. The parts are now in assembled position for proper operation, and due to the knurling of the studs 134 they remain rigidly in the position assumed in Figure 10.

60 The toggle spring 118 comprises two pairs of arms 142 and 144 connected together by a pair of coils 146. The coils are under such tension as to tend to spread the arms 142 relative to the arms 144, thereby acting as a resilient thrust element between pivot points 154 and 148. The pivot point 154 is in the form of a notch in a stud 150 threaded into an opening 152 of the actuated lever 96, while the pivot point 148 is in the form of a pair of out-turned ends on the extremities of the toggle spring arms 144 and received in openings 149 of the arms 122 of the actuating lever 116. This is perhaps best shown in Figure 5, wherein it will be noted that the two arms 142 have a cross piece 156 between them for engaging in the notch 146. The purpose of threading the stud 150 in the lever 96 is so that it can be vertically adjusted for a purpose which

will hereinafter appear. The stud is slotted as illustrated in the drawings for the purpose of providing sufficient friction to hold the stud at any adjusted position. The stud, of course, is spread enough by opening the slot to give the desired amount of holding friction.

The degree of tipping of the actuated lever 96 may be controlled by adjusting screws 158 and 160, the lower ends of the screws striking the cover plate 94 when the valves V⁴ and V² are open as shown in Figures 2 and 3 respectively. The screws 106 and 108 are adjustable to give proper clearance for the upper ends of the valves V² and V⁴ with relation to the under surface of the seal-off diaphragm 92 when the valves are in closed position, as evident in Figures 2 and 3.

To lock the screws 106, 108, 158 and 160 against loss of adjustment, two spring wires 162 are provided and lie against the screws and the stud 159 in the manner shown in Figure 1. These wires are under bending tension so as to frictionally engage the screws and thus hold them normally adjusted except when a screwdriver is applied thereto.

The purpose for making the stud 52 adjustable in the sleeve 54 is to insure that the actuating lever 116 will swing the same distance to the right as to the left for making the snap action of the spring 118 equal in both directions. The adjusting sleeve 74 is first adjusted to give the desired travel of the stud 52 and then the stud is adjusted relative to the sleeve 54 until the throw of the lever 116 is equal on both sides of a center line from the pivot center of the actuated lever 96 to the stationary pivots 124. The stud 159 may be adjusted upwardly or downwardly depending on whether a stronger or weaker snap is desirable, as adjustment upwardly increases the spreading tendency of the spring 118 and adjusting it downwardly decreases its strength.

In Figure 6, I show how my positive relay may be connected with a main 164 supplying compressed air to the relay and to a device for controlling the relay, such as a pneumatic thermostat 166. The main, it will be noted, is connected to the opening 2, and a pressure operated valve 168, such as the type having a bellows operator, is connected to the opening 3 which serves as an outlet. The relay in this case is "direct-acting."

When the thermostat 166 increases the pressure supplied from the main 164 to the diaphragm 36 until it reaches the control point determined by the setting of the adjusting spring 58, the lever 116 will be moved from the solid line position of Figure 2 to another position, such as the one shown by dotted lines. This brings the toggle spring 118 from its full line position to its dotted line position, in which latter position the pins 124, 132, 148 and 154 have almost reached a position of alignment or dead center. The toggle spring 118 in attempting to open up or spread its arms 142 and 144 will thereupon snap the actuated lever 96 from the position of Figure 2 to the position of Figure 3, as soon as the pressure of the spring under the valve V⁴ is enough to move the actuated lever 96 to the dead center position. Thus the spring under the valve V⁴ assists in the final movement of the actuated lever past the dead center position, and similarly when the parts are operated in the opposite direction, the spring under the valve V² assists in moving the actuated lever past the dead center position. The strength of the valve springs therefore enters into this operation and affects to some extent the differential of the relay. There is also a slight modi-

fication of the action due to air pressure under the seal-off diaphragm 92, but since the air on the portion over the valve V⁴ is at the same value as the air pressure over the valve V², they are substantially equalized and the modifying effect is very slight.

The adjusting or main spring 58 and the diaphragm 36 due to their relation in alignment with each other minimize the pivot load, thus making the relay very sensitive.

The actuating lever 116 moves the actuated lever 96, the two levers being independent of each other, except through the snap spring connection 118, and thus the lever 96 operates freely without having to drive back through the lever 116 and be opposed by the main spring or the diaphragm.

It will also be noted that the two pivots 124 are spaced a substantial distance from each other and so are the two pivots 132 and the two pivots 148; whereas the pivot 154 is located in a plane substantially balanced between the two pivots 148. This results in the lever 116 being held against any cocking action relative to its pivots and the forces are so equalized or balanced as to minimize any lateral bias of the toggle spring on the actuating lever 116. The differential of operation of the relay is thereby minimized due to elimination of friction caused by binding action and remains constant throughout successive operations of the relay without variation from the original differential spread. I am thus insured that the relay will operate similarly throughout its entire life.

The "in-line" arrangement of the adjusting spring 58 and the diaphragm 36 also makes it possible to have a wide degree of adjustment, for instance, between 4 and 17 pounds per square inch where the relay is designed for a maximum of 17 pounds.

Referring again to Figure 6, air flow will be to valve 168 through the valve V² as indicated by the solid line arrow when the relay is in the position of Figure 3 (with valve V² open and valve V⁴ closed). The valve 168 (normally open) will therefore be closed.

When the pressure is reduced in the opening 1 by the thermostat, the control point lowered by the amount of differential will finally be reached, whereupon the relay will assume the position of Figure 2, permitting air flow from the diaphragm of the valve 168 to atmosphere through the opening 4 as indicated by the dotted arrow, and thereby opening the valve 168.

The relay may be hooked up for reverse action, as shown in Figure 7, wherein the valve 168 (again normally open) has the air discharged from it as indicated by the solid line arrow when the thermostat 166 increases the pressure of the air from the main 164 to the opening 1 of the relay. Valve V² is open at that time for permitting air to bleed from the bellows of the valve 168 to open it. When the thermostat 166 is in position for reducing the air pressure from the opening 1 of the relay, the valve V⁴ is open to permit air from the main 164 to enter the bellows of the valve 168, as indicated by the dotted arrow and thereby close the valve 168.

When my relay is to be used for diverting air with respect to two different branches, such as the branches 170 and 172 in Figure 8, the main 164 is connected with the opening 3 and the thermostat 166, when permitting increase of air pressure to the opening 1, results in air from the main passing through the valve V² to the opening 2 and the branch 170, as shown by the solid

line arrow. When the thermostat 166 decreases the air pressure from the opening 1, the valve V⁴ opens for diverting air from the main 164 to the branch 172 instead of the branch 170, as indicated by the dotted arrow.

Some changes may be made in the construction and arrangement of the parts of my device without departing from the real spirit and purpose of my invention, and it is my intention to cover by my claims any modified forms of structure or use of mechanical equivalents, which may be reasonably included within their scope without sacrificing any of the advantages thereof.

I claim as my invention:

1. In a device of the character disclosed, the combination of an actuated element for positioning in either one of two positions, an actuating element, an adjusting spring in alignment therewith for opposing the movement of said actuating element, a pivoted lever, said actuating element having one portion pivoted thereto and another portion connected with a diaphragm, said lever and said diaphragm constituting the supporting means for said actuating element and moved in response thereto, said spring being adjustable to change the control point of said pivoted lever, and a toggle spring connecting said lever with said actuating element, said toggle spring having a pair of arms pivoted respectively to said lever and said actuated element, and a coil connecting said arms together and constraining them to move away from each other.

2. In a control structure, the combination of an actuated element for positioning in either one of two positions, an actuating element therefor, a lever operatively connected with said actuating element and moved in response thereto, and a toggle spring connection between said lever and said actuated element, and having a pair of arms pivoted to said lever and a second pair of arms pivoted to said actuated element, and having a coil connecting each pair of said arms to the other pair thereof and constraining them to diverge in relation to each other.

3. In a device of the character disclosed, an actuated element movable between two positions, an actuating element, a range spring opposing movement of said actuating element, and a toggle spring connecting said actuating element with said actuated element, said toggle spring having two pairs of arms with one pair pivoted to one of said elements and the other pair pivoted to the other of said elements, and a coil connecting one of said arms of each pair together and constraining their outer ends to move away from each other.

4. In a device of the character disclosed, a frame, an actuating element and an adjusting spring supported by said frame in alignment with each other, an actuating sleeve between said actuating element and said adjusting spring, an actuating lever having an opening surrounding said sleeve and pivoted relative to said frame, said actuating lever having pivot openings, pivots projecting from said actuating sleeve and into said pivot openings, said pivots being slidable inwardly relative to said sleeve to permit the sleeve to enter said actuating lever opening and the pivots to move outwardly to engage in the pivot openings of said actuating lever, an actuated element for operation by said actuating lever, and an operative connection between said actuating lever and said actuated element.

5. In a control structure, the combination of a frame, an actuating element and an adjusting spring supported by said frame, an actuating sleeve between said actuating element and said spring, an actuating lever having an opening surrounding said sleeve and pivoted relative to said frame, pivots projecting from said actuating sleeve and pivotally coacting with said actuating lever, said pivots being slidable inwardly to permit said sleeve and the pivots to enter said actuating lever opening and the pivots to then move outwardly to pivotally engage said actuating lever, said pivots being retained frictionally in their outward positions, control mechanism for operation by said actuating lever, said control mechanism having an actuated element, and an operative connection between said actuating lever and said actuated element.

6. In a control device, a frame, actuating means and an actuating sleeve mounted in said frame, said actuating sleeve being responsive to said actuating means, an actuating lever having an opening surrounding said sleeve and pivoted relative to said frame, said actuating lever having pivot openings, pivots projecting from said actuating sleeve and pivotally coacting with said pivot openings of said actuating lever, an actuated element, and an operative connection between said actuating lever and said actuated element comprising a toggle spring.

7. In a control device, actuating means including an actuating sleeve, an actuating lever pivotally mounted and having an opening surrounding said sleeve, said actuating lever having pivot openings, pivots projecting from said actuating sleeve and into said pivot openings of said actuating lever, said pivots being slidable inwardly relative to said sleeve to permit it to enter said actuating lever opening and said pivots to move outwardly to engage in said pivot openings, an actuated element for operation by said actuating lever, an operative connection between said actuating lever and said actuated element comprising a toggle spring having a central U-shaped arm terminating in coils, said coils having terminal ends constituting a double arm, and means for pivoting one of said arms to said actuating lever and the other of said arms to said actuated element, said coils tending to spread said arms.

8. In a device of the character described, an actuating element, an actuated element for operation by said actuating element, an operative connection between said actuating element and said actuated element comprising a toggle spring having a central U-shaped arm terminating in coils, said coils having terminal ends constituting a double arm, and means for pivoting one of said arms to said actuating element and the other of said arms to said actuated element.

9. In a device of the character disclosed, the combination of an actuated element for positioning in either one of two positions, an actuating element, an adjusting spring in alignment therewith for opposing the movement of said actuating element in response to a rise in pressure thereagainst, a pivoted lever, said actuating element being pivoted thereto and supported thereby in conjunction with a connection of said actuating element with a diaphragm at a point spaced from said pivotal connection and moved in response thereto, said spring being adjustable to change the control point of said pivoted lever, and a snap acting connection between said lever and said actuated element.
